UNITED STATES PATENT OFFICE.

REYNOLD KOHLHAAS, OF PHILADELPHIA, PENNSYLVANIA.

RIBBON-LOOM.

SPECIFICATION forming part of Letters Patent No. 699,879, dated May 13, 1902.

Application filed August 29, 1901. Serial No. 73,733. (No model.)

To all whom it may concern:

Be it known that I, REYNOLD KOHLHAAS, a citizen of the United States, residing at Philadelphia, county of Philadelphia, and State of 5 Pennsylvania, have invented a certain new and useful Improvement in Ribbon-Looms, of which the following is a specification.

My invention relates to a new and useful improvement in ribbon-looms, and relates to 10 that class of ribbon-looms in which two or more shuttles are used for weaving ribbons of two or more colors, and my invention applies to that part of the mechanism of the loom which actuates and shifts the shuttles 15 backward and forward; and the objects of my invention are to construct this mechanism in such a manner that it will be compact and take up but little space in the loom, and this mechanism will be located underneath 20 the loom and not extend up above the same, so as to cut off the light, as in the case of the apparatus now used.

Another object of my invention is to so construct the device that it will allow the same 25 to be actuated from any point of the loom, and it will be entirely automatic in throwing out one set of shuttles and putting in operation the set desired.

With these ends in view this invention 30 consists in the details of construction and combination of elements hereinafter set forth and then specifically designated by the claims.

In order that those skilled in the art to 35 which this invention appertains may understand how to make and use the same, the construction and operation will now be described in detail, referring to the accompanying drawings, forming a part of this specification, in which—

Figure 1 is an elevation of one side of the lathe with my invention applied thereto; Fig. 2, a horizontal section through the lathe upon the line 2 2 of Fig. 1; Fig. 3, an elevation 45 on the opposite side of the lathe from Fig. 1; Fig. 4, a section on the line 4 4 of Fig. 3, showing the manner in which movement is communicated to the different shuttles by the different racks; Fig. 5, a detail view of one of the clutch-pulleys; Fig. 6, a detail perspective view of a band - wheel, showing the crank-arm connected therewith;

Fig. 7, an end elevation of my invention, showing the lathe in section; Fig. 8, an enlarged detail side elevation of the clutch-pulleys with the cords attached thereto; Fig. 9, a diagram of a pair of the clutch-pulleys, showing the cords connected to the rack and the rack being in the extreme position in one direction; Fig. 10, a similar view to Fig. 9, 60 showing the rack in the extreme position in the opposite direction; Fig. 11, a side elevation of the lathe with my invention applied thereto, showing the manner in which the pulleys would be arranged when only two 65 shuttles are used; Fig. 12, a plan view of Fig. 11, and Fig. 13 an end view of Fig. 11.

In ribbon-looms in which more than one shuttle is used the lathe is composed of two parts—namely, the back lathe, which is represented in the drawings by 1 and which is stationary, and the front lathe, (represented in the drawings by 2,) which is movable up and down vertically. The shuttles or races for the shuttles are carried in the front or 70 movable lathe and are raised and lowered with the same. The object of raising and lowering the front lathe is to bring into operation different series of shuttles carrying different colors, and only one series of shuttles 75 is operated upon at one time. Thus the mechanism which throws the shuttles must be operated upon automatically, so as to throw the right series of shuttles, according to the height 80 the front lathe is raised—as, for instance, if 85 the front lathe is in its lowest position, as shown in Fig. 1, the upper line of shuttles are designed to be thrown. When the front lathe is raised one step, the next line of shuttles directly beneath will be operated, and so 90 on, according to the number of series of shuttles in the bank. This raising of the front lathe forms no part of my invention and may be accomplished in any manner desired and usually regulated by jacquard mechanism. 95 My invention relates entirely to the mechanism for throwing the shuttles and means whereby this mechanism is regulated automatically by the raising and lowering of the front lathe.

In my invention the shuttles are designed to be thrown in the manner now in common use—that is, by means of racks 3, which are adapted to reciprocate backward and forward

within guideways running longitudinally of the front lathe. These racks are adapted to be always in mesh with the fixed gear-wheels 4. Each of said gear-wheels is also in mesh 5 with the different series of shuttles 5, which shuttles have racks formed upon one side of the same to mesh with the gear-wheels. The shuttles 5 are adapted to slide within races, and the warp which forms the ribbon is adapted 10 to pass through the lathe between the shuttle-races, and the shuttles are of such a length that in passing backward and forward across this space the rack upon the shuttle will be engaged by the gear-wheel upon the opposite 15 race before it is out of mesh with the gear-wheel of the race from which it started. Thus it is simply necessary to reciprocate the racks backward and forward to throw the shuttles.

As far as I have described is old and an ordinary construction, the following description will apply to my invention.

Extending outward from the back or stationary lathe 1 is a framework 6. Bearings are formed in this framework, in which are journaled shafts 7 and 8. Upon the shaft 7 is journaled loosely a series of clutch-pulleys 9, there being as many clutch-pulleys in this series as there are series of shuttles in the lathe, and upon the shaft 8 are journaled loosely another 30 series of clutch-pulleys 10, corresponding in number to the clutch-pulleys 9. These clutch-pulleys are arranged in pairs, one member of the pair being upon one shaft and the other member upon the other shaft and directly opposite one another. Each of these pairs of pulleys operate to reciprocate one rack.

In the drawings, in Figs. 1 to 11, inclusive, I have illustrated the lathe as constructed for four series of shuttles, and therefore there 40 would be four clutch-pulleys upon each of the shafts 7 and 8. Each of the clutch-pulleys has formed in its periphery two grooves. In one of the grooves of the clutch-pulley 9 is adapted to lie the cord 11, which is secured 45 to the periphery of the pulley at one end and passes upward over one of the series of idle pulleys 12 and then passes around a pulley 13, which is journaled in the front lathe, and the other end of the cord 11 is secured to one 50 of the racks 3. Within the corresponding groove of the clutch-pulley 10 is adapted to lie the cord 14, one end of which is secured to said pulley, and this cord then passes upward and over one of the series of idle pulleys 12 and extends parallel with the lathe in 55 the opposite direction to the cord 11 and passes around one of the pulleys 15, journaled in the lathe, and the other end of the cord 14 is also secured to one of the racks, so that for 60 each pair of clutch-pulleys 9 and 10 there will be a pair of cords 11 and 14, extending from these pulleys to the rack. These pulleys are adapted to reciprocate the rack. The clutch-pulleys 9 and 10 are adapted to be revolved by mechanism hereinafter to be described, one in one direction and the other in 65 the opposite direction, the same distance and

at the same rate of speed, so that when one of the cords 11 or 14 is wound upon one of the pulleys the opposite cord will be unwound from the other pulley, and thus the cords will always remain taut; but the rack will be reciprocated backward and forward as the pulleys are revolved backward and forward. Each pair of clutch-pulleys 9 and 10 are 75 adapted to reciprocate a different rack, and as only one rack is to be reciprocated at a time, and the rack which is reciprocated depends upon the height to which the front lathe is raised, it is necessary that the clutching mechanism which clutches the desired pair of pulleys will be operated automatically by the raising and lowering of the front lathe, and this mechanism I will now describe in detail.

The clutch-pulleys 9 and 10 are journaled 80 loosely upon the shafts 7 and 8, and these shafts are adapted to be rotated backward and forward by means of the band-wheel 16. This band-wheel is adapted to be reciprocated backward and forward by means of the 90 two straps 17, which are wound upon the band-wheel in opposite directions, and these straps are adapted to be pulled alternately by mechanism connected with the loom, such as a double crank-shaft which may be adjustable as to the pull. This forms no part of my invention, as any suitable means can be employed which would alternately pull the straps or bands 17, and these straps and bands can be run over pulleys to any point of the 100 machine and operated therefrom either above or below the lathe. The shafts 7 and 8 are adapted to be revolved in opposite directions to one another by the band-wheel 16, and this is accomplished by means of the gear-wheel 105 18, which is adapted to be revolved in the same direction as the band-wheel, and this gear 18 meshes with the gear 19, journaled upon the shaft 7. The gear 18 also meshes with an idle gear 20, which in turn meshes 110 with the gear 21, journaled upon the shaft 8. The motion from the band-wheel is not communicated directly to the gear 18, but is transmitted through a crank 22, which crank is secured to the same stud as the gear-wheel 115 18. This crank-arm 22 is slotted at 23, and in this slot is adapted to slide a block 24, which block is secured to the rear face of the band-wheel, near the periphery of the same. The band-wheel 16 is journaled upon a stud 120 which is secured in the bracket 25', and this bracket is slotted vertically at 26', so that the stud and the band-wheel may be raised or lowered, and thus the band-wheel may be placed upon the same line as the stud to 125 which the crank 22 is secured or may be lowered so as to be out of line with said crank-stud. When it is out of line with the crank-stud, one-half of the revolution of the band-wheel will bring the block 24 at a point nearer the crank-stud than when it is at the point directly opposite such position, and the speed 130 will be consequently increased as the block is brought nearer the center. This is for the

purpose of increasing the speed transmitted to the clutch-pulleys, and thereby to the racks and shuttles, when the shuttles are at one-half of their travel, and will decrease the speed at the end of the travel. Thus when the band-wheel 16 is set off the center with the crank-stud the shuttles will commence at a comparatively slow speed, and the speed will be accelerated until one-half of the movement is completed and then will gradually decrease to the end. This variation of the speed of the shuttles is for throwing the same quickly through the shed of the warp, so that in weaving very wide ribbons the shed will not close upon the shuttles and at the same time the shuttles will start slowly and stop slowly. Of course in narrow ribbons this variation of speed would not be necessary. Then the band-wheel could be adjusted so that its pivotal point would be in a direct line with the crank-stud, and the speed of the shuttle then would be the same throughout its travel. The shuttles are designed to be reciprocated only when the band-wheel is pulled in one direction. The reversing of the band-wheel is only for the purpose of returning the mechanism to its normal position.

It is obvious that to reciprocate the racks only one of the pair of cords 11 and 14 can be pulled upon at one time, and therefore only one of the pair of clutch-pulleys 9 and 10 are to be actuated. Thus the clutching mechanism must be such that the clutch-pulleys 9 and 10 may be alternately connected and disconnected from the shafts 7 and 8, for the opposite pulley must be revolved in the opposite direction to the actuated pulley and at the same rate of speed, so as to allow the opposite cord of the pair to be unwound to allow the rack to travel and at the same time keep the cord taut. I will now describe the means by which I accomplish this movement.

Each of the clutch-pulleys 9 and 10 has pivoted to the same the dog 25, as clearly shown in Fig. 8. These dogs are pivoted to the pulleys at the point 26 and are adapted to be held in their normal position by means of the spring 27, so that their outer edge 28 projects beyond the periphery of the pulleys, a pin 29 limiting this movement. In the outer end of these dogs is formed a notch 30.

31 represents pawls which are secured to the shafts 7 and 8 and adapted to revolve therewith. The nose 32 of the pawl is adapted to enter the notch 30 in the dog 25, and thereby carry the pulley around with it in its revolution, and when the dog 25 is in its normal position, as shown in the left-hand pulley of Fig. 8, the pawl can revolve freely within the pulley without engaging the same. For the purpose of pressing the dog 25 upward at the proper time I provide the spring-cams 33, which are pivoted to the framework 6 at the point 34 and are held upward in contact with the peripheries of the pulleys by means of the springs 35. The cords 11 and 14 are se-

cured to the pulleys 9 and 10, so that the dog 25 which is carried by the opposite pulley to the one being revolved by the pawl will be directly over its cam 33 at the limit of its movement, so that the cam will press the dog upward, so as to be engaged by its pawl in the next movement of the same. The dog upon the opposite pulley, which has been in engagement with its pawl, will not stop over the cam, so that when the pawls 31 are revolved backward by the alternate rotation of the band-wheel 16 this dog as soon as it is freed from engagement with its pawl will spring outward into the position shown at the left of Fig. 8, so that in the next forward movement of the pawl it will not engage this dog, but engage the dog of the opposite pulley of the same pair. Thus it will be seen that the pulleys cannot make a full revolution, because if they did each of the dogs would stop upon its cam 33, there being one of the spring-cams under each pulley. Thus each pawl would engage its dog and prevent any movement whatsoever.

The operation of this clutching mechanism is as follows: As the band-wheel 16 is rotated in one direction one of the pawls 31 will engage its dog 25 and revolve the clutch-pulley 95 of that pair of pulleys which is set for operation the required distance, and the cords are so tied and adjusted to the pulleys that when this pulley has made the required revolution the other pulley, which has been revolved in the opposite direction, will be stopped so that its dog is directly over its spring-cam 33, and thus the dog will be forced into position to be engaged by its pawl. The band-wheel at this point is then reversed, the pawl traveling 105 backward. This pawl will be allowed to pass the raised dog, because of the fact that both the dog and the cam can swing downward by reason of the spring 35, and then resume its normal position after the pawl has passed. 110 When the band-wheel and pawls have reached their limit in this retrograde movement, the band-wheel is again reversed, which will cause the pawls to travel forward, and then the opposite pawl will engage the dog upon 115 the opposite pulley to the one formerly engaged, and so on, the dogs upon the pulleys being engaged alternately, the revolution of one pulley leaving the dog upon the opposite pulley in position to be next engaged. 120

I have found by experience that in case the loom is stopped before the pulleys have reached the limit of their movement the weight of the jacquard mechanism or other means may cause the shafts to travel backward a slight distance, and this backward movement might be sufficient to then remove the pawls from the dog before the completed movement. The dogs would then instantly spring outward and would not be engaged by the pawl when the movement is resumed. To obviate this, I provide upon one side of the dogs the latch 36, which is pivoted to the dog at the point 37. A notch 38

is formed upon the pulley, and a light spring 39 tends to normally hold the latch out of engagement with the notch; but this latch is in such a position that when the nose 32 of the 5 pawl enters the notch 30 of the dog it will also push the latch 36 into engagement with the notch 38, and thus the dog will be held in position to be engaged by the pawls until the latch is removed from the notch. Thus 10 if the nose 32 of the pawls is removed from the notch of the dogs a slight distance before the movement is completed when the movement is resumed it will again engage the dog; but after the movement has been completed 15 and the pawls travel backward in their retrograde movement the finger 40, which is carried by the pawl, will strike the latch 36 and disengage it from the notch, so as to allow it to spring back in its normal position, 20 and thus when the pawl resumes its forward movement it will not engage the dog.

As before mentioned, the opposite pulley to the pulley being actuated by the pawl revolves in the opposite direction to the one 25 actuated at the same rate of speed and the same distance. This movement may be communicated from the actuated pulley to the other of the same pair in any suitable manner; but I prefer to employ the following 30 manner: A cord 41 is provided for each pair of pulleys, and one end of this cord is secured to one pulley of the pair and the other end is secured to the opposite pulley and adapted to rest in the second groove of such 35 pulleys. The loop of this cord 41 is then adapted to pass down and around one of the idle pulleys 42, which pulleys are adjustable vertically upon an arm 43, which extends downward from and is carried by the front or 40 vertically-moving lathe. Then when one of a pair of pulleys is actuated by the pawl so as to be revolved forward the cord 41 will be wound upon this pulley, and thereby will be caused to unwind from the opposite pulley, 45 which will revolve such pulley in the opposite direction.

As it has been heretofore described that the only pulleys which are actuated by the revolution backward and forward of the shafts 50 7 and 8 are those pulleys whose dogs are pressed upward by the spring-cam 33, all of the pawls revolve with each of the shafts, and so to throw in another series of shuttles it is only necessary to revolve the pulley so that 55 that pair of clutch-pulleys which is adapted to reciprocate that series of shuttles will be turned in such a position that their dogs will work in conjunction with their spring-cams upon each movement of the band-wheel. The 60 cords 11 and 14 are so tied to the pulleys that the proper set of clutch-pulleys will each time be brought in the proper position to have their dogs actuated by the cam as the front lathe is raised or lowered to bring in action 65 the different set of shuttles. Of course all the other dogs of the other pulleys will not come in contact with their cams at the limit

of the movement of the band-wheel in either direction. Thus if the front lathe 2 is raised the pulleys 12 and 42 will be raised with it, 70 as also the cords 11 and 14, which will be pulled upon equally by the raising of the lathe. The clutch-pulleys 9 and 10 being attached to the back lathe, it will be held stationary, and thus will be compelled to turn 75 as the cords 11 and 14 are pulled upward, and these cords are so tied and adjusted to each pair of pulleys that it will bring the dogs of the proper pair of pulleys in the proper position so as to be engaged by the pawls, and 80 thus the proper rack and series of shuttles will be reciprocated.

The pulleys 15 may be adjusted longitudinally of the lathe for the purpose of tightening the cords in any convenient manner, 85 here illustrated as by means of the screw-rods 44, which are swiveled through the framework 45 and threaded through the studs upon which the pulleys 13 and 15 are journaled, 90 said studs adapted to slide within slots formed in the lathe.

46 represents connections adapted to slide in grooves formed in the front lathe, and to these connections are connected the cords 11 and 14 of one-half of the racks, for when 95 there are four shuttles in the bank two of the racks 3 will be above and two below the line of the shuttles, and these connections 46 are for the purpose of operating the upper racks. 100

In Figs. 11, 12, and 13 I have illustrated how my invention would be constructed when only two series of shuttles would be used. The pulley-wheels 9 and 10 would then be all journaled upon the same shaft and the cords 105 11 and 14 and 41 would all operate the same as they do upon the pulleys, before described, set upon the separate shafts. The idea of making the two shafts 7 and 8 instead of one is simply for the purpose of economizing 110 space, for when there are four or more series of shuttles used it will necessitate the use of four or more pairs of clutch-pulleys. Therefore if this large number of clutch-pulleys 115 were journaled upon the same shaft it would make the apparatus too wide, and that is the reason why they are divided up upon two shafts for the purpose of reducing the width; but when there are only two or three shuttles used they may be placed upon one shaft, 120 and this will somewhat simplify the mechanism, as the gear-wheels 18, 19, 20, and 21 may be dispensed with. The rest of the apparatus is the same as has been described and operates in exactly the same manner. 125

The advantages of my invention are that the whole mechanism for shifting the shuttles is confined in a very small space and is so compact that it can be placed underneath the lathe, which is of great advantage over 130 the mechanism now used, which projects upward from the lathe and cuts off the light from the work. Another advantage of my invention is that the bands which are secured

to the band-wheel can be run over pulleys to any point of the machine and operated from any shaft desired, either above or below the shuttles, and a further advantage is the 5 quickness and accuracy with which the mechanism can be adjusted to vary the speed of the shuttle and the simplicity of the mechanism by which the different series of shuttles are thrown into and out of action automatically by the raising and lowering of the front lathe.

Of course I do not wish to be limited to the exact construction here shown, as slight modifications could be made without departing 15 from the spirit of my invention.

Having thus fully described my invention, what I claim as new and useful is—

1. In combination with a ribbon-loom of the character described, bearings secured to 20 the back lathe, clutch-pulleys journaled loosely transversely of the lathe and adapted to be supported by said bearings, said clutch-pulleys arranged in pairs, one pair for each series of shuttles, two cords for each pair of 25 pulleys, one end of one cord being attached to one pulley of the pair, one end of the other cord attached to the other pulley of the pair, idle pulleys journaled in bearings on the lathe-beam, one of the cords of each pair of 30 clutch-pulleys adapted to pass from said clutch-pulleys in one direction and pass around the idle pulleys and be attached to the rack, the other cord of the same pair of clutch-pulleys adapted to pass in the opposite 35 direction around another idle pulley and be attached to the rack, said idle pulleys so placed that when the cords are pulled alternately the rack will be reciprocated, means for rocking the transverse shaft upon which 40 the clutch-pulleys are journaled a predetermined part of one revolution backward and forward, clutching mechanism adapted to alternately connect first one and then the other of the clutch-pulleys of each pair to their 45 shafts each time the shafts are rocked in one given direction, means whereby the pulley in clutch with the shaft will rotate the other pulley of the pair in the opposite direction at the same rate of speed so that the cord connected to one of the pulleys of the pair will 50 be wound upon the same, and the cord connected to the other pulley of the pair will be unwound from the same, means whereby the clutching mechanism is thrown in and out of 55 engagement with different pairs of clutch-pulleys automatically by the raising and lowering of the front lathe, substantially as described and for the purpose set forth.
2. In an apparatus of the character described, one or more shafts adapted to extend transversely across the lathe-beam, bearings secured to the back lathe in which said shaft or shafts are journaled, clutch-pulleys journaled loosely upon said shaft or shafts, said 60 clutch-pulleys arranged in pairs, one pair for each series of shuttles carried by the lathe, two cords for each pair of clutch-pulleys, one end of one of the cords of each pair attached to one of the clutch-pulleys of each pair, and one end of the other cord attached to the other pulley of the same pair, idle pulleys, two for each pair of clutch-pulleys, journaled in the front lathe, one of the cords of each pair of clutch-pulleys adapted to pass around one pulley of each pair of idle pulleys, the other cord adapted to pass around the other idle pulley, and both cords adapted to be secured to one rack, said idle pulleys so arranged in the front lathe that when the cords are alternately pulled the rack will be 70 reciprocated, a band-wheel journaled upon a suitable bearing extending from the back lathe, two bands or straps secured to the band-wheel and wound upon the same in opposite directions, said bands or straps adapted to 75 be alternately pulled so as to rock said band-wheel a predetermined part of one revolution backward and forward, means for transmitting this backward-and-forward motion to the transverse shaft or shafts, clutching mechanism whereby one pair of pulleys journaled upon the transverse shaft is alternately connected to said shaft so as to be revolved therewith when the shaft or shafts are moved in one direction, means whereby the clutch-pulley 80 which is in clutch with the shaft will cause the other pulley of the same pair to rotate in the opposite direction the same distance and at the same rate of speed, whereby by the cord connected to one pulley will be 85 wound upon the same, and the cord connected to the other pulley will be unwound from the same, the cords tied to the clutch-pulleys at such a point that when the front lathe is raised certain distances the clutch-pulleys will be 90 so revolved as to throw into engagement the clutching mechanism of a certain set of clutch-pulleys, and means for giving to the actuated clutch-pulleys a variation of speed, said means adapted to increase the speed at one-half of the revolution, and diminish the speed 95 toward each end of the stroke, substantially as and for the purpose specified.
3. In combination with a device of the character described, clutching mechanism consisting of a dog pivoted to each of the clutch-pulleys, a spring adapted to hold the outer edge of the dogs normally beyond the periphery of the pulleys, a notch formed in the dogs, pawls secured to the transverse shaft or shafts and adapted to rock therewith, spring-cams pivoted to the back lathe, springs adapted to normally hold said spring-cams in contact with the periphery of the pulleys, and said cams adapted to act so as to push the 110 dogs inward so that the notch in the dog will lie in the path of travel of the pawls whenever said dogs are stopped in the proper position, means whereby only one pair of clutch-pulleys are adapted to work in conjunction 115 with the clutch mechanism so as to reciprocate one of the racks at a time, a vertically-moving front-lathe beam forming a part of the loom to which this device is attached, said 120

pairs of clutch-pulleys adapted to be thrown in and out of contact with the clutching mechanism by the raising and lowering of the front lathe, each pair of clutch-pulleys adapted to be so revolved relative to one another that both the dogs pivoted to said pulleys will never be in contact with the spring-cams at the same time, but the actuated clutch-pulleys will be so rotated that the dog of the opposite pulley of the pair engaged by the pawl will be brought in contact with its cam at the limit of its movement and forced in the path of the travel of the pawl so as to be engaged by the same upon the next move-

ment of the pawl, means for locking the dogs in their raised position when engaged by the pawl, and means for releasing said locking mechanism when the pawl has made about one-half of its retrograde movement, substantially as and for the purpose set forth.

In testimony whereof I have hereunto affixed my signature in the presence of two subscribing witnesses.

REYNOLD KOHLHAAS.
